UNITED STATES PATENT OFFICE.

ADOLPH L. FOELL, OF BUFFALO, NEW YORK, ASSIGNOR TO DONNER STEEL COMPANY, INC., A CORPORATION OF NEW YORK.

COOLING BED.

Application filed November 6, 1920. Serial No. 422,227.

To all whom it may concern:

Be it known that I, ADOLPH L. FOELL, a citizen of the United States, and a resident of Buffalo, in the county of Erie and State 5 of New York, have invented a new and useful Improvement in Cooling Beds, of which the following is a specification.

This invention relates to cooling beds.

Among the objects of the invention are to 10 provide means for handling the hot metal bars as they are delivered to the cooling bed so as to give them an initial straightening movement, means to further straighten and hold them straight as the bars cool, and 15 means to insure a uniform cooling of all sides of the hot metal stock while it passes across the cooling bed. And particularly this invention is concerned with giving the hot bars a sliding or rolling movement as 20 they are delivered to the cooling bed producing an initial impact of the hot bars against an aligned row of stops, for the purpose of straightening the bars by means of their own inertia at a time when they are plastic 25 enough to be affected by such a movement.

Referring to the drawings Fig. 1 is a cross section through a cooling bed embodying this invention; Fig. 2 is a side elevation of a portion of the cooling bed showing diagrammatically the path of movement of certain members thereof; and Fig. 3 is an enlarged view, similar to that of Fig. 2, showing diagrammatically the movement of hot bars on the cooling bed, and the path of travel 35 of the movable members thereof.

Heretofore cooling beds have been provided for handling hot bars as they come from a rolling mill, comprising a set of stationary parallel spaced apart supporting 40 members with an intermediate set of movable lifting and carrying members, the latter members being mounted upon frames which are given a circular or elliptical movement. The movable members were so situated that 45 substantially one-half of their cycle of movement was above the top of the fixed members. Consequently, in each cycle the movable members rose to the level of the fixed members, picked up hot bars supported thereon, 50 carried them upward, forward and downward, through a curved path of travel, and redeposited them upon the fixed supporting members at a distance beyond the point of pick up. This distance has varied in exist-

ing mechanisms from an inch to a foot or 55 more.

Beds of this step-by-step conveyor type have also been built in which the supporting members were in the form of racks, that is, having their upper surfaces cut into notches, 60 forming serrations. And these serrations on the fixed racks have been arranged in rows from end to end of the cooling bed so that the notches in adjacent racks were in alignment, that is, having their sides in the same 65 planes, forming in effect troughs, such troughs being separated by aligned rows of serrations. Likewise the lifting members have been in certain cases notched, the notches in adjoining racks being aligned in 70 rows running from end to end of the series of lifting members.

The present invention in its preferred form comprises a cooling bed with fixed members having aligned rows of specially formed 75 notches, and lifting members having also aligned rows of specially formed notches, the notches in the lifting members being of a different form from those of the supporting members, and especially positioned to attain 80 certain definite objects. Although the term "notches" is here used, it will be apparent from the description below that the notches of this machine are incidental, and that the upper surfaces of both the lifting and supporting members are in effect divided into 85 series of inclined portions with bounding stops at the bottoms of the incline. The stop portions extend up to the tops of the next following inclines, and so on. 90

Referring to the drawings which illustrate the present invention, Fig. 1 shows diagrammatically the main elements of a mechanism embodying this invention. It comprises the foundation members 1 and 2. Upon the latter member is supported a central run-out, comprising driven rollers 3 and 4, having concave surfaces, as illustrated. These rollers are carried by a shaft 5, mounted in a bearing member 6 which is supported by 100 suitable frame members extending to the foundation. It will be understood that a series of the rollers 3 extends from the end of the guide trough leading from the last pair of rolls of the mill, throughout the length 105 of the cooling bed. A hot bar from the last pass of the rolls is delivered upon the first of the series of concave rollers 3, and by these

rollers is drawn positively down the run-out along the middle portion of the cooling bed. The rollers are spaced apart a suitable distance and may have idle rollers between them, as is well known in cooling bed construction. In practice the parts hereinafter described are duplicated on the right of the series of run-out rollers 4, similar to rollers 3. A hot bar is delivered to rollers 3, racked off 10 to the left, the next hot bar is delivered to rollers 4, racked off to the right, and so on. Only one side of the cooling bed is here illustrated.

Adjacent to the run-out members 3 and 15 placed perpendicular to the path of the run-out in a horizontal position, are a series of supporting members 10, carried upon a structural frame-work which holds them in fixed position. These supporting members 20 have on their upper surfaces serrations 11 forming intervening notches 12, as illustrated. These notches and serrations as illustrated are all similar, and all of the members 10 are similar, the serrations 11 25 and the sides of notches 12 in adjoining members 10 being aligned horizontally from end to end of the cooling bed in rows parallel to the path of run-out members 3, with the corresponding sides of the notches 30 of each row lying in the same planes. At their outer ends the members are formed into plane portions 10^a and 10^b, at slightly lower levels than the bottoms of the notches 12. A limiting guard member 13 is positioned 35 at the outer end of the members 10, to prevent any metal bars from escaping from the side of the cooling bed.

Positioned between the fixed supporting racks 10 are a series of movable lifting and 40 carrying racks 20 which likewise have their upper surfaces formed into serrations 21 and intervening notches 22.

These movable racks are preferably provided at intervals of about one lifting rack 45 after each fourth fixed rack, although this spacing may be varied to make every other rack a movable one, or to place them further apart according to the needs of any particular mill.

50 All the movable racks 20 are rigidly supported on I-beams 23 and cross members 24, which are mounted upon a series of movable beams 25. These are suspended by pivotal connections 26 at their outer ends to link 55 members 27, which are carried by pivotal connections to the fixed frame members 29.

The movable racks 20 are all horizontally aligned and the serrations 21 and notches 22 are horizontally aligned from end to end 60 of the cooling bed, forming rows of troughs throughout the length of the carrying portion of the cooling bed. The inner ends of the beams 25 are free, the frame formed by I-beams 23 and 24 being supported thereupon. At an intermediate position the

I-beams 25 are supported on a shaft 35 through eccentrics 36 keyed upon the shaft, the I-beams being carried upon these eccentrics by means of circular bearing loops 37. The shaft carries a counter-weight 38 70 adapted to counterbalance the lifting movement of the eccentrics 36 in the bearing 37, as will be obvious.

A suitable motor and control is provided for driving the shaft 35 intermittently. 75 This has the effect of causing that portion of beam 25 which is directly above the center of shaft 35 to move in a circular direction, but since the outer end of the beam 25 is supported by a swinging link 27, the effective travel of the inner end of the beam 25 is elliptical. Consequently the lifting and carrying members 20, supported upon the inner end of beam 25, have a forwardly-tilted, elliptical movement, as illustrated in 80 Figs. 2 and 3. This elliptical movement is not entirely uniform along the racks 20 since toward their outer ends the ellipse becomes more tilted and more flattened out, as illustrated. But effectively it is an ellipse 85 such as that indicated in Fig. 3.

The lifting racks 20 are so positioned with respect to the fixed supporting racks 10 that the cycle of movement of the lifting racks is substantially one-half above the 90 outer surface of the supporting racks, and one-half below that surface.

All the serrations and all the notches on each of the lifting racks are similar except at the inner ends of the lifting members. 100 There the lifting racks have elongated terminal portions 45, the upper faces of which form inclined portions 46 slanted down and inward from the ends, as clearly shown in the drawings. These inclined portions 46 105 are longer than the sides of any of the notches, and terminate in abutting members 47, which have inner faces 48 inclined at substantially right angles to the slopes 46. Thereafter the remainder of the supporting 110 surfaces of the lifting rack are divided into the serrations and notches 21 and 22 above referred to. These are formed by very short and steep forwardly inclined stops 49 and comparatively long and less steep rearward inclines 50.

The extensions 45 of the lifting members are adapted to extend beneath the run-out 3, as illustrated in Fig. 1.

The operation of this cooling bed is as 120 follows:

When a piece of hot metal stock, as for example, round bar B, is delivered from the rolls of the mill upon the run-out, it is carried on the driven rollers 3 until it has 125 entirely passed through the rolls and both ends are within the length of the cooling bed. Thereupon the electric motor which drives shaft 35 is set in motion and shaft 35 is driven one complete turn. This lifts the 130

beams 25 and consequently the entire series of lifting racks 20 and carries them through an elliptical path as illustrated by the dotted lines 60 and 61 in Figs. 2 and 3. The 5 inner terminal projection 45 of the lifting racks 20 move inward, upward, and forward, so that the hot bar B supported in the run-out rollers 3 is picked up upon the inclined surfaces 46, at a point near their top, as 10 illustrated in dotted lines at the top of Fig. 3. While the lifting racks are moving upward and forward the bar B rolls over by its own weight, moving forward down the inclines 46 until it strikes the abutting faces 15 48 in the first notch 22^a of the lifting members, thus coming to rest in the position in the carrying notch shown in dotted lines at the top of Fig. 3, indicated by the reference numeral B¹. In the position illustrated as B¹ the bar is carried 20 upward in an elliptical path 60, then downward and backward until it comes in contact with and is deposited upon the slope 13^a of the fixed supporting bars 10, at the point indicated in Fig. 3 by the bar B².

25 The supporting members then pass on downward, leaving the bar in the position indicated by B², whereupon it rolls forward by gravity down the slope 13^a until it is stopped by impact with the stop 14^a of the first fixed notch 12^a, thus coming to the position B³, as indicated clearly in Fig. 3.

At the next revolution of the shaft 35 the bar B³ is picked up from its position illustrated, by the rearwardly inclined slope 50^a 35 near the top of the said slope, at the point indicated by B⁴, and as the movable rack goes on upward and forward the hot bar rolls backwardly down the slope 50^a to the position indicated as B⁵ in the bottom of the movable notch. It will be observed that this rolling movement is in reverse direction to the first rolling movement down the two inclines 46 and 13^a. The bar B⁵ is carried 40 in the bottom of the notch 22^b, which is the first of the similar movable notches, upward, then downward and slightly backward until it reaches the position indicated at B⁶, at which point it is deposited upon the slope 13^b at approximately the position indicated, 45 whereupon it rolls forward down the slope 13^b, coming to rest in the fixed notch 12^b, between the walls 13^b and 14^b, in the position marked B⁷. Thereafter it is picked up, rearwardly rolled, put down and forward rolled, 50 as above described, at each revolution of the shaft 35 until it is finally deposited upon the fixed slope 13^k, down which it rolls and then is kicked out upon the horizontal portion 10^a by the heels of racks 20. After a number 55 of bars have collected on the portion 10^a they are raked off laterally onto the portion 10^b, whence the stock is moved longitudinally to a shear mechanism, as is customary in cooling bed constructions, and as will be 60 65 readily understood without description here.

The effect of this apparatus and the operation just above described is that immediately after the hot stock is delivered from the rolls it is picked up on a surface which is inclined at an angle sufficient to cause the 70 hot bar to roll or slide down the inclined surface until it is stopped by a row of aligned abutments at the bottom of this first inclined portion. These abutments are aligned in the same plane from end to end 75 of the cooling bed, as are also the surfaces of the inclined portions 46. The bar turns over and over on the inclines 46, and then comes to rest with a considerable impact against the aligned stops or abutments 48, 80 which are substantially at right angles to the incline 46. The straightening effect of rolling a hot bar upon a plane surface is well known, as is the straightening effect of dropping a hot bar into a straight trough, 85 the sides of which join an angle of approximately 90°. The rolling and impact tend to positively straighten the hot bar if it is crooked and the supporting of it in such a notch tends to keep it straight in all directions. 90

It is also well known that the straightening effect of a cooling bed is practically negligible after the first few seconds following the receipt of a hot bar, since at the ordinary rolling temperature, the plasticity of the bar permitting straightening by gravity or by rolling action is quickly lost by the cooling and consequent stiffening of the bar. 95

By the present construction the rolling 100 action backward and then forward at each transfer from notch to notch tends to keep the bar in the straight condition which is produced by the rolling action incident to its delivery to the first row of notches and 105 also tends to more uniformly cool it both by reason of its turning over in transit and also because different sides of the bar are turned downwardly successively. Thus, the drafts of cold air which constantly pass 110 upwardly through the cooling bed and come in contact with the underside of the bar first are brought into contact with different sides of the bar, which is, therefore, more uniformly cooled than where it is supported on only 115 one side in its travel across the cooling bed. This tends to prevent cambering of the hot bar by reason of unsymmetrical cooling.

The forwardly inclined elliptical travel of the lifting racks has an important function, 120 especially when other than round bars are being handled on the cooling bed. As illustrated in Fig. 3, at the pick-up of a hot bar from any of the fixed notches 12 the lifting rack is traveling forward as well as 125 upward, so that the inertia of the hot stationary bar helps to give it a rearward rolling or sliding movement on the rearwardly inclined slope 50 of the lifting notch. This has been found in practice to be suffi- 130

cient to cause square bars to roll over down the incline 50, and to cause irregular sections that cannot turn over to slide down even when the slope of the incline 50 is even when the slope of the incline 50 is 5 less than the angle of repose.

Square bars after coming to rest are normally held in the moving notches in such position that they are already tilted forward, resting on their forward under side. 10 Therefore, when deposited at or near the top of the incline 13, on edge, their center of gravity is ahead of the edge on which they are laid down, so that they topple forward and turn over on the way down the incline. The deposit is made at a point of the elliptical travel that is nearly vertical.

The cooling bed is ordinarily duplicated on each side of the central run-out and a hot bar is delivered first on one side of the run-out and then on the other. But each side of the cooling bed operates independently and therefore it is sufficient to describe the members of one side only.

The many uses and advantages of this 25 invention will be apparent to those familiar with the art.

I claim:

1. A cooling bed comprising a run-out, 30 a series of fixed supporting members beside the run-out, a set of movable lifting and carrying members positioned between the supporting members, said lifting and carrying members being formed with terminal inclined portions at their inner ends adjacent to said run-out and a series of aligned stops 35 at the bottom of said inclined portions, and means to move the lifting and carrying members in a curved path, said moving members being adapted to pick up hot stock 40 from the run-out on the upper ends of the inclined portions, whereby to cause the hot stock to roll down the inclined portions against the aligned stops at the bottom thereof.

2. A cooling bed comprising fixed supporting members and intermediate lifting members, a run-out adjacent to the inner ends of the fixed members, and inclined terminals on the inner ends of the lifting members adapted to pick up a hot bar from the run-out upon the upper portion of said inclined terminals and to deliver it to the fixed supporting members after it has moved by gravity down the inclined portions.

3. A cooling bed comprising a series of fixed supporting members and a series of intermediate lifting and forward carrying members, each of said members having 50 notched supporting surfaces, the notches in each set of members being aligned from end to end of the cooling bed, the lifting members having elongated inclined inner terminal members, and means to drive the lifting members whereby to pick up a hot bar

from the run-out at the top of said inclined members, and after the bar has moved down the inclined side of said notch to deliver it to the top of the first notch on the fixed supporting members.

4. A cooling bed comprising a series of fixed supporting racks having their upper surfaces formed into a series of forwardly inclined planes with aligned stops at the bottom of said planes, a series of lifting and carrying racks mounted intermediate the supporting racks, said lifting racks having their upper surfaces divided into a series of rearwardly inclined planes and aligned stops at the bottoms of said planes, and mechanism for driving the lifting and carrying racks in a forwardly inclined elliptical path.

5. A cooling bed comprising fixed supporting racks having their upper surfaces 85 divided into a number of forwardly inclined planes with aligned stops at the bottoms of said planes, movable lifting racks adapted to travel intermediate the fixed racks, said lifting racks having their upper surfaces divided into a number of rearwardly inclined planes having aligned stops at the bottoms of said planes, and means to move the lifting racks in a forwardly inclined elliptical path.

6. A cooling bed comprising a run-out, fixed supporting racks having aligned rows of notches for retaining hot stock delivered to them from the run-out, lifting and carrying racks positioned intermediate the fixed 100 racks, said lifting racks having inclined extensions adapted to pick up the hot stock from the run-out, aligned stops at the bottom of said inclined extensions, and rearwardly inclined portions adapted to 105 co-operate with the notches of the fixed racks, whereby to pick up hot stock from the fixed racks upon the rearwardly inclined portions, and means to drive the lifting racks in a forwardly inclined elliptical 110 path.

7. A cooling bed comprising a run-out, a series of horizontal supporting bars arranged perpendicular to the run-out, and situated adjacent thereto, a series of horizontal lifting and carrying bars positioned intermediate the fixed supporting bars, the lifting and carrying bars having inclined terminals extending beneath the run-out, and a series of aligned stops at the bottoms 115 of said inclined terminals, and means to drive the lifting and carrying members to pick up hot stock from the run-out upon the tops of said inclined portions and to deliver it to the fixed supports.

8. A cooling bed comprising a set of fixed supporting members having their upper surfaces divided into aligned inclines and stops, a set of intermediate movable lifting and carrying racks having their upper surfaces 120

divided into aligned inclines and stops, means to drive the movable members in an elliptical path, the inclines of the movable racks being positioned relative to the inclines of the fixed racks so that on the upward movement, the tops of the moving inclines pass through a position of substantial alignment with the bottoms of the inclines on the fixed racks.

10 9. A cooling bed comprising a set of fixed supporting members having their upper surfaces divided into aligned inclines and stops, a set of intermediate movable lifting and carrying racks having their upper surfaces divided into aligned inclines and stops, means to drive the movable members in an elliptical path, the inclines of the movable racks being positioned relative to the inclines of the fixed racks so that on the downward movement the bottoms of the moving inclines pass through a position of substantial alignment with the tops of the inclines on the fixed racks.

20 10. A cooling bed comprising a set of fixed

supporting members having their upper surfaces divided into aligned inclines and stops, a set of intermediate movable lifting and carrying racks having their upper surfaces divided into aligned inclines and stops, means to drive the movable members in an elliptical path, the inclines of the movable racks being positioned relative to the inclines of the fixed racks so that on the upward movement the tops of the moving inclines pass through a position of substantial alignment with the bottoms of the inclines on the fixed racks, and so that on the downward movement the bottoms of the moving inclines pass through a position of substantial alignment with the tops of the inclines on the fixed racks.

In testimony whereof, I have hereunto set my hand.

ADOLPH L. FOELL.
